CLAIM

The ornamental design for a cosmetics holder, as shown and described.

DESCRIPTION

FIG. 1 is a perspective view of a cosmetics holder, showing our new design;

FIG. 2 is a side elevational view thereof, and the opposite side view being a mirror image thereof;

FIG. 3 is a front elevational view thereof;

FIG. 4 is a rear elevational view thereof;

FIG. 5 is a top view thereof; and,

FIG. 6 is a bottom view thereof.

The dot-dot-dash broken lines immediately adjacent to the claimed areas in the views represent the boundaries of the design and form no part thereof.

The broken lines in the figures illustrate the portions of the design that form no part of the claimed design.

None of the broken lines form any part of the claimed design.
